UNITED STATES PATENT OFFICE.

GEORGE RAMSAY, OF SAULT STE. MARIE, ONTARIO, CANADA, ASSIGNOR TO THE NATIONAL REFINING COMPANY, OF CLEVELAND, OHIO, A CORPORATION OF OHIO.

OILER.

1,185,823.

Specification of Letters Patent.

Patented June 6, 1916.

Application filed February 3, 1915. Serial No. 5,956.

To all whom it may concern:

Be it known that I, GEORGE RAMSAY, a subject of the King of England, residing at Sault Ste. Marie, in the Province of Ontario, 5 Canada, have invented certain new and useful Improvements in Oilers, of which the following is a specification.

This invention relates generally to oilers, and particularly to that class of such 10 devices having an individual control for each oiling line.

More specifically the invention relates to an oiler comprising a casing having an upper and lower compartment separated by 15 wire mesh basket or filter tray, and provided with suitable openings adapted to receive suitable discharge and control devices arranged to regulate the dropping or feeding of oil to the several supply pipes, the amount 20 of oil passing through the devices being indicated through each individual sight glass.

The invention may be further briefly summarized as consisting in the construction and combination of parts hereinafter set 25 forth in the following description, drawings and claims.

Referring to the drawings, Figure 1 is a top plan view of the device; Fig. 2 is a vertical section; Fig. 3 is an end elevation; 30 and Fig. 4 is an enlarged detail view showing the control.

In carrying out the invention any preferred form and construction of parts may be employed so long as they possess the 35 necessary characteristics, but I have shown one arrangement which is effective and in such embodiment, the casing comprises an upper portion 1 connected by a suitable shoulder 2 with a lower well portion, 3, the 40 bottom 4 of which being provided with suitable openings 5 for the several individual oil feeds. Connected to the exterior of the well portion 3 is a suitable hanger or bracket 6 extending down below the casing and provided with a plurality of clips 7, each spanning a pipe connection 8 leading to a part 45 to be oiled. Each of the pipes is connected above the lower portion of the bracket 6 with a suitable sight glass connecting member 9 of any preferred construction adapted to support the lower end of a sight feed glass 10. This glass passes into an upper connection 11 provided with a chamber 12

into which projects a nozzle 13. Each of the connections 11 is provided with an upwardly 55 extending nipple 14 threaded into one of the openings 5 of the casing. A suitable oil feed opening 16 is arranged in this connection through the top and through the threaded nipple 14 for the reception and 60 feed of oil to the nozzle projection 13. Within the several openings 5 and extending up into the casing is a plurality of oil feed control devices, and each of these devices comprises a tubular casing 17 extending 65 up to a point near the top of the main casing, and provided at a point above the bottom with suitable oil feed openings 18 leading to the interior of the tube. At a point near the top these tubes are provided 70 with air vent openings 19. Each tubular casing is provided below the openings 18 with a valve seat plug 20 secured within the end of the tube as by soldering or by a drive fit, and each of these plugs has a centrally disposed oil feed opening 21 with a valve seat 22 at the top. This valve seat 22 receives a needle valve 23 less in diameter than the inner bore of the tubular casing and preferably formed integral with a 80 threaded shank 24 threaded into the upper end of the tubular casing 17. At the extreme upper end of the threaded shank is a knurled head 25 utilized in manipulating the valve, and on this threaded shank below 85 this head is a check nut 26 for holding the valve in any adjusted position. The air vent openings 19 are below the threaded shank 24 in the various adjustments of the valve. 90

Resting on the shoulder 2 formed around the casing is a filtering device in the form of a tray, comprising side walls 27 and end walls 28. These walls are turned inward to form an inwardly extending flange 29 95 to which is secured the bottom 30 of wire mesh. This bottom is provided with openings 31 which receive the several oil feed controlling devices.

In order to indicate the fluid level within 100 the casing a suitable gage is provided and it comprises a connection 32 leading from the bottom of the tank to a point outside where it has secured to it a suitable gage glass connection 33 receiving a gage glass 105 34 which extends up to a point near the top

of the casing where it is provided with a cap 35. In this way the level of the oil within the casing is readily seen.

Secured to the back of the casing is a lug 5 or ear 36 adapted to receive a bolt 37 passing through a strap 38. This strap extends upward and receives a tongue 39 formed integral with the cover 40. This tongue beyond the strap is provided with lateral 10 projections 41 which hold the tongue within the strap.

Having described my invention, I claim:—

1. An oiler comprising a casing having an upper portion and a lower well portion separated by a horizontally disposed shoulder, a strainer or filter tray within the casing arranged upon said shoulder, a plurality of discharge devices arranged in the bottom of the well portion of said casing, and a plurality 15 of oil feed control devices for said discharge devices, and each comprising a tubular casing supported in the main casing above the corresponding discharge extending up through the strainer or filter and having oil feed openings leading into the interior of the tubular casing below the strainer or filter, a valve seat plug arranged in the lower end of said tubular casing below the oil feed openings, a threaded valve 20 shank engaging the upper end of said tubular casing, a needle valve formed integral with said threaded shank and coöperating with the valve seat plug, means for manipulating said threaded shank, and means for holding the same in any adjusted position.

2. In an oiler, a main casing comprising an upper and lower portion separated by an inwardly extending annular shoulder, a filter tray supported on said shoulder and comprising side and end walls bent in at the bottom to form an inwardly extending flange and the bottom of foraminous material, a bracket extending downward from the lower portion of the casing on the outside thereof, 45 a plurality of discharge pipes connected to said bracket, a sight glass connection carried by each discharge pipe above the bracket, a sight glass carried by each connection, an upper sight glass connection for receiving the upper end of the glass and securing the bottom of the casing, and provided with an oil nozzle communicating with the casing,

and a plurality of oil feed controlling devices, each consisting of a tubular casing in alignment with the corresponding discharge 55 extending through the foraminous bottom and having oil feed openings through the wall below the foraminous bottom, a valve seat plug within the tubular casing having a centrally disposed opening with a valve seat 60 at the upper end, a threaded shank engaging in the upper end of the tubular casing, an inlet valve less in diameter than the bore of the tubular casing and having a valve at the lower end for engagement with the corresponding valve seat, a knurled head on each threaded shank, and a knurled nut engaging the threaded shank above the end of the tubular casing adapted to engage the same to hold the valve in any adjusted position. 70

3. An oiler comprising a casing having an upper portion and a lower well portion separated by a horizontally disposed shoulder, a strainer or filter tray within the casing arranged upon said shoulder, a plurality of discharge devices arranged in the bottom of the well portion of said casing, and a plurality of oil feed control devices for said discharge devices, and each comprising a tubular casing supported in the main casing 75 above the corresponding discharge extending up through the strainer or filter and having oil feed openings leading into the interior of the tubular casing below the strainer or filter, a valve seat plug arranged 80 in the lower end of said tubular casing below the oil feed openings, a threaded valve shank engaging the upper end of said tubular casing, a needle valve formed integral with said threaded shank and coöperating 85 with the valve seat plug, means for manipulating said threaded shank, means for holding the same in any adjusted position, a bracket extending downward from the main casing, a plurality of oil pipes supported in 90 said bracket, and a sight-feed arranged between each oil pipe and the corresponding controlling device.

In testimony whereof I affix my signature in presence of two witnesses as follows.

GEORGE RAMSAY.
